United States Patent Office.

JAMES HUTCHISON, OF NEWARK, NEW JERSEY, ASSIGNOR TO EDWARD C. SAMPSON, OF NEW YORK CITY.

Design No. 3,343, dated January 19, 1869.

DESIGN FOR A FLOOR OIL-CLOTH PATTERN.

The Schedule referred to in these Letters Patent and making part of the same.

To all whom it may concern:

Be it known that I, JAMES HUTCHISON, of Newark, County of Essex, State of New Jersey, have originated and designed a new Pattern for Floor Oil-Cloths, Carpets, or other fabrics, of which the following is a full, clear, and exact description, reference being had to the accompanying specimens or drawings, making part of this specification, and marked or designated as No. 3, which fully represent said design, and are sufficient, without further aid, to enable any person skilled in the art to repeat it for practical use.

The colors employed for the different portions of this design may be varied to suit the convenience or taste of the manufacturer.

What I claim as my invention, and desire to secure by Letters Patent, is—

The design or pattern for floor oil-cloths, carpets, or other fabrics, shown and described.

JAMES HUTCHISON.
